UNITED STATES PATENT OFFICE

114,962

DESIGN FOR A SUITCASE OR THE LIKE

Joseph Ortner, Newark, N. J.

Application January 28, 1939, Serial No. 82,646

Term of patent 3½ years

To all whom it may concern:

Be it known that I, Joseph Ortner, a citizen of the United States, residing in Newark, county of Essex, and State of New Jersey, have invented a new, original, and ornamental Design for a Suitcase or the like, of which the following is a specification, reference being had to the accompanying drawing, forming part thereof.

In said drawing, Fig. 1 is a perspective view of a suitcase or the like, showing my novel design; Fig. 2 is a fragmentary perspective view of a corner of the suitcase of the like in Fig. 1, on a slightly enlarged scale; Fig. 3 is a fragmentary side elevational view of a lower portion of the corner in Fig. 2; and Fig. 4 is a fragmentary top plan view of the same. The dominant features of my design reside in the portions shown in full lines.

I claim:

The ornamental design for a suitcase or the like, as shown and described.

JOSEPH ORTNER.
